UNITED STATES PATENT OFFICE.

WILLIAM H. SPENCER, OF NEW YORK, N. Y., ASSIGNOR TO I. P. FRINK, INC., OF NEW YORK, N. Y., A CORPORATION OF NEW YORK.

ADJUSTABLE REFLECTOR.

Application filed October 31, 1923. Serial No. 671,951.

To all whom it may concern:

Be it known that I, WILLIAM H. SPENCER, a citizen of the United States, residing in the city, county, and State of New York, **5** have invented certain new and useful Improvements in Adjustable Reflectors, of which the following is a specification.

This invention relates more especially to reflectors for electric lamps of standard **10** types which are made in different sizes according to the lighting effects, required of them.

The primary object of this invention is to provide an improved adjustable device **15** whereby a given reflector may be adapted for use with various sizes of lamps as well as for the use of a given size of lamp in different lighting relations with respect to the reflector. More specifically stated, the present **20** invention contemplates a reflector which may be used with lamps of different sizes without varying the position of the lamp filament in relation to the reflecting surface. My invention also contemplates the provision **25** of suitable means in a reflector for producing a variation in the light diffusion or spread of light with the same reflector and same lamp.

Other and further objects of invention **30** will appear in the specification, reference being had to the accompanying drawings which exemplify my invention in a preferred embodiment and in which—

Figure 1 is a vertical section of the reflector in collapsed position to adapt it for use with a 75 watt electric lamp, parts being shown in elevation;

Figure 2 is a similar vertical section showing the telescopic neck in partly extended position to accommodate a 100 or **40** 150 watt lamp with the filament thereof maintained in the same relative position to the reflecting surface;

Figure 3 is a similar vertical section of the reflector having the neck fully extended to accommodate a 200 watt lamp with its incandescent filament held in the same relative position to the reflecting surface;

Figure 4 is a similar vertical section of the reflector in partially extended position showing a 75 watt lamp in a position intermediate to upper and lower positions to

which the lamp may be moved by the adjustment of the telescopic neck; and

Figure 5 is a fragmentary bottom plan **55** view of the preferred form of reflector.

As shown in Figure 1 of the drawings, the reflector 1 is provided with an upwardly tapered neck 2 having its upper edge curved outwardly to form a collar 3. Within the **60** neck portion 2 of the reflector is a telescopic extension section comprising a cylindrical portion 4 provided with an outwardly flared lower flange portion 5 having a uniform degree of taper and around its upper **65** edge with an outwardly curved collar 6 which as shown in Figure 1 is adapted to nest within the collar 3 and to be supported thereby. Within the intermediate section of the collapsible neck is an inner section **70** comprising a cylindrical portion 7 arranged within and slidably contacting with the cylindrical portion 4 of the intermediate section, a lower flared flange portion 8 having a uniform degree of taper and an upper outwardly flared collar 9 which nests **75** within and is supported by the collar 6 of the intermediate section. Suitable means for supporting the reflector from a lamp socket 10, are provided in the present embodiment of my invention by a hood 11 suspended from said socket 10 and provided with a depending flange 12 within which the adjustable set screws 13 are mounted for engaging under the outwardly flared collar **80** of the upper section of the telescopic neck or of two or more sections in collapsed position. As shown in Figure 1, the screws **85** 13 are arranged to engage under the three nested collars 3, 6 and 9, since the neck sections are collapsed so as to bring the center of illumination 14 of an incandescent lamp 15 in predetermined position with respect to the reflecting surface of reflector 1.

According to Figure 2 of the drawings, **95** an incandescent lamp 16 is arranged within the reflector 1 so as to bring its light center 17 in the same relative position to the reflecting surface as that occupied by light center 14 in Figure 1. For this purpose, **100** the screws 13 are arranged to engage under the nested flanges 6 and 9 of the intermediate and inner sections of the telescopic neck, the flared lower edge 5 of the interme-

diate section being drawn into contact with the flared inner wall of the section 2 of the reflector 1.

In the positions of the parts shown in Figure 3, the set screws 13 engage under the flange 9 of the inner section 7 only, the telescopic sections being fully extended so that the flared lower edges 5 and 8 are nested within the upwardly tapered neck 2 of the reflector 1. By this adjustment, the light center 18 of the 200 watt lamp 19 is brought into the same relative position to the reflecting surface of reflector 1 as that occupied by the light centers 14 and 17.

Referring now to Figure 4, the 75 watt lamp 15, is shown with its light center 14 raised above its position shown in Figure 1, by partly extending the telescopic neck of the reflector. According to this figure of the drawings, modifications of the light flux are shown by lines of different characters in connection with the adjustment of the 75 watt lamp with respect to the reflector 1. Thus, with the telescopic neck completely collapsed, the light center of this lamp would lie at 20 so that the light flux would be substantially the same as that shown in Figure 1. The light flux for the middle position is represented on this figure by the dash lines originating from light center 14. The light flux for the uppermost position corresponding to the full extended position

of the reflector neck, is shown in dash and dot lines to originate from the upper light center 21.

35

I claim:

1. The combination with a reflector having an integrally formed upwardly contracted tapered neck provided with a flange turned outwardly from its smallest diameter at the top, of a section telescopically connected thereto and comprising an upper cylindrical portion slidably contacting with the inner wall of said tapered neck at the top and a lower portion provided with a uniform taper adapting it to be closely embraced by the inner tapered wall of said reflector neck adjacent its smallest diameter.

2. The combination with a reflector having an integrally formed upwardly contracted and uniformly tapered neck, of a plurality of telescopically connected sections provided with uniformly tapered lower portions corresponding to the upper portion of said tapered neck and with progressively longer cylindrical portions, extending above said tapered lower portions, the upper edges of said tapered neck and the cylindrical portions of said telescopic sections being provided with outwardly turned flanges whereby said reflector may be suspended at different elevations with respect to an electric light socket.

WILLIAM H. SPENCER.
